(57) **CLAIM**

The ornamental design for a wind turbine nacelle, as shown and described.

DESCRIPTION

FIG. 1 is a perspective view of a wind turbine nacelle showing our new design;

FIG. 2 is another perspective view thereof;

FIG. 3 is a front side view thereof;

FIG. 4 is a right side view thereof;

FIG. 5 is a rear side view thereof;

FIG. 6 is a left side view thereof;

FIG. 7 is a top plan view thereof; and,

FIG. 8 is a bottom plan view thereof; and,

FIG. 9 is another perspective view thereof.

The broken lines shown represent unclaimed subject matter and form no part of the claimed design.
